UNITED STATES PATENT OFFICE.

RICHARD W. BURNETT, OF CHICAGO, ILLINOIS.

ANGLE-COCK HOLDER.

Application filed October 7, 1922. Serial No. 593,125.

This invention relates to improvements in angle cock holders.

One object of the invention is to provide an improved angle cock holder to be employed with train pipes and which is characterized by simplicity of construction, efficiency in operation, and economy of manufacture.

A specific object of the invention is to provide an angle cock holder having an extension to engage the usual hexagonal nut of an angle cock, the extension being made as a separate piece from the holding bracket proper and attached thereto so that, in the event of breakage of the nut-engaging extension, the latter may be readily replaced at small cost without the necessity of replacing the entire angle cock holder.

Another object of the invention is to provide a novel and efficient pipe holding key to be employed with an angle cock holder or train pipe anchor.

In the drawings forming a part of this specification, Figure 1 is a side elevational view of an improved angle cock holder showing my improvements in connection therewith. Figure 2 is an end elevational view of the holder shown in Figure 1, the pipe, however, being shown in section. Figures 3 and 4 are views corresponding respectively to Figures 1 and 2 and illustrating another embodiment of the invention. Figures 5 and 6 are views corresponding respectively to Figures 1 and 2, illustrating a still further embodiment of the invention. Figure 7 is a top plan view of the construction illustrated in Figure 5. Figure 8 is a view similar to Figure 1, illustrating a still different embodiment of the invention. And Figure 9 is an elevational view of the improved key, detached.

In said drawings, and referring first to the construction illustrated in Figure 1, 10 indicates the end sill or buffer block or other suitable fixed portion at the end of a car, to which the improved angle cock holder is adapted to be secured. As shown, the angle cock holder comprises, broadly, a holding bracket proper A; a clamping key B; and a separately formed nut-engaging lug plate C. A portion of the train pipe is indicated at 11, the latter having secured thereto an angle cock, a portion of which is shown, the angle cock having the usual hexagonal nut section 12.

The holding bracket proper A has an

inclined arm 13 suitably flanged at its upper end, by which it may be riveted to the member 10 of the car as by the rivets 14, it being understood that the arm 13 may assume different formations, dependent upon the formation and location of the fixed part of the car to which the holding bracket is to be secured. At its outer end, the arm 13 is formed into a substantially inverted U-shaped structure having laterally spaced depending arms 15-15 united by a top cross section 16. The arms 15-15 are provided with transversely aligned vertically elongated slots 17-17 within which is adapted to be driven the clamping wedge key B, the latter being described with particularity herein-after. On its inner side, the U-shaped portion of the holding bracket A is provided with opposed inwardly extending pipe bearings 18-18, it being understood that the train pipe 11 will be wedged thereagainst when the key B is driven home. In the particular embodiment of the angle cock holder shown, the pipe can be elevated into position from the bottom between the arms 15-15 although in this respect it will be understood by those skilled in the art that the bracket may be designed with just a circular opening through which the pipe will be passed when applied to the car.

The top cross connecting section 16 of the bracket is formed with a longitudinally extending shallow groove 19 defined by upstanding lips 20 within which groove is seated one end of the plate C.

The plate C will preferably be made from rolled steel, cut to the required shape. The inner end thereof-21-which is seated within the groove 19, is rigidly attached to the bracket A as by rivet 22, the bottom end of the rivet 22 being accommodated in a suitable recess 23 provided on the inside of the bracket A so as to clear the pipe. The outer end 24 of the plate C will ordinarily be downwardly offset from the inner end 21, as shown in Figure 1, so as to engage one face of the nut 12 and thus hold the latter against turning and always in its required position.

The bracket A will ordinarily be made of malleable iron and obviously, were the nut-engaging extension thereof cast integrally therewith, there would be danger of said lug extension becoming broken, inasmuch as it is the part most exposed to injury and relatively weakly supported. By employing a separately formed plate such as that shown at C,

the danger from injury to the nut-engaging lug is not only decreased but, should it become broken, the plate C can readily be replaced by another similar plate without the necessity of replacing the entire holder.

Referring to the construction illustrated in Figures 3 and 4, the arrangement of holding bracket A' and key B' (except as hereinafter described) is the same as the corresponding members shown in Figures 1 and 2. In the arrangement of Figure 3, a separately formed nut-engaging lug plate C' is employed, the latter being cut from a plate and having its inner end upturned as indicated at 121. The holding bracket A' is formed with initially upstanding malleable flanges 120—120 on the top thereof which are adapted to be bent inwardly toward each other over the plate C' to the positions indicated at 120'—120' in Figure 4, so that, when the flanges are so bent, the plate C' will be held rigid with the bracket A' and prevented from becoming disassembled with respect thereto. In this arrangement, should injury occur to the plate C', it is evident that a new one may be substituted therefor by lifting up the flanges 120 and bending them back again on to the substituted plate.

Referring next to the construction illustrated in Figures 5 and 6, the arrangement of the holding bracket A², except as herein-after described, and the key B², is the same as the correspondingly referenced parts shown in Figures 1 and 2. In the arrangement of Figures 5 and 6, the holding bracket A² is formed with a pair of longitudinally separated parallel upstanding flanges 25 and 26 on the top thereof, said flanges 25 and 26 having horizontally longitudinally aligned slots 27 and 28, respectively therein. The vertical web of the arm 213 of the brackets A² will be cut away for a short distance as indicated at 29 to accommodate, when necessary, the inner end of the nut-engaging plate C². The latter consists of a preferably rectangular cut section of plate of such width and thickness as to be snugly accommodated within the slots 27 and 28. When the plate C² is cut to form it will also preferably be slit so as to provide two longitudinally spaced and aligned tongues 30 and 31, each of which is left attached at its inner end, that is, the end toward the right as viewed in Figures 5 and 6, with the main body of the plate C². The tongue 30 is so located that, when the plate C² is positioned to the extreme right as shown in Figure 5, the tongue 30 may be bent downwardly to the position indicated at 30' in Figure 5 so as to engage behind the flange 25 and thereby prevent the plate C² from being withdrawn from the bracket A². This is the position which will normally be taken by the plate C² but under some service conditions, it may be necessary to extend the outer end

of the plate C² to a point considerably toward the left of that shown in Figure 5, for which purpose the second tongue 31 is provided so that it may be similarly bent down from the plane of the plate C² to engage behind the flange. Referring to Figure 6, it will be noted that the recess to accommodate the train pipe 211 is formed somewhat differently from that shown in Figures 2 and 4. In Figure 6, the recess has no separately defined bearings for the pipe but is gradually converged at its upper end, as indicated at 218 so that the pipe 211 will be wedged therebetween to provide two of the points of contact to effect the clamping of the pipe.

Referring to the construction illustrated in Figure 8, the arrangement is substantially the same as that shown in Figures 1 and 2 except that the plate C³ is made longer and has two rivet openings 32—32 therein spaced longitudinally so as to adapt the plate C³ to be held in either adjusted position by employing the proper rivet hole 32.

Referring now to the specific form of the clamping key employed with the angle cock holder and shown best in Figure 9. Said key, designated in Figure 9 generally by the reference character B⁴ is cut from sheet plates and tapered toward one end, having a bottom flat edge 40, wide vertical edge 41 and top inclined edge 42. At its narrower end, the key B⁴ is slit along the line 43 so as to provide an upper tang 44 and a lower tang 45. In actual practice, the lower tang 45 will preferably be made longer than the tang 44 and the latter will have its end 46 left blunt, for the purpose hereinafter described. It will be noted that the direction of the slit 43 is such as to render the tang 45 gradually narrower from its outer free end 47 toward its inner end where it merges with the main body of the plate. This is of importance in the construction of the key, inasmuch as the tang 45 is the one employed to hold the key in position after it is driven home. When the key is in its proper position, the tang 45 will be hammered around the adjacent portion of the holding bracket and by reason of the gradual narrowing in width of the tang 45 toward the point of its coalescence with the main portion of the key, the bend will naturally occur immediately adjacent the portion of the bracket about which it is being bent, since this will obviously be the narrowest and therefore the weakest section of the tang which can be bent. With this arrangement, I am sure of obtaining the bend in the holding tang as close to the bracket as possible and hence eliminate possibility of the key becoming loose and having free play in the bracket after it has been placed in position. Were the holding tang of gradually weaker section toward its free end, the bend in the tang would not come close to the portion of the bracket

around which it is necessary to hammer and consequently the bend, in many instances, would be sufficiently removed from the bracket as to allow the key to rattle in position. The shorter tang 44 is employed to hammer the key out when desired, the end 46 thereof being left blunt for this purpose.

I have herein shown and described what I now consider the preferred manner of carrying out the invention, but the same is merely illustrative and I contemplate all changes and modifications that come within the scope of the claims appended hereto.

I claim:

1. An angle cock holder comprising: a bracket adapted to be secured to a relatively fixed support and provided with a pipe-receiving opening and means for clamping the pipe therein, said bracket being provided on the top thereof with an extension with an opening therethrough and a shoulder inwardly of said opening; and a separately formed plate extended partly through said opening and having its outer end positioned to engage the nut of the angle cock, said plate being provided with a plurality of longitudinally aligned integral tongues adapting the plate for adjustable connection with the bracket, one of said tongues being offset to engage behind said shoulder and thereby prevent withdrawal of the plate accidentally from the bracket.
2. In an angle cock holder, the combination with a bracket adapted to be secured to a fixed part of a railway car and provided with downwardly extending spaced arms to permit insertion and removal of a pipe therebetween; of detachable means co-operable with said arms for retaining the pipe in position; and a separately formed, replaceable lug plate located on the upper side of said bracket, said plate having its forward end extended and adapted to engage the nut of an angle cock carried by said pipe to prevent turning thereof, said bracket having a longitudinally extending recess within which said plate is received, said plate having an integrally formed section co-operable with a shoulder integrally formed on the bracket to prevent movement of the plate outwardly toward the angle cock, said plate being normally held in fixed position but removable upon deformation of one of said co-operable inter-engaging parts of the plate and bracket, the pipe and angle cock being removable from the bracket without disturbing the lug plate.

In witness that I claim the foregoing I have hereunto subscribed my name this 25th day of September, 1922.

RICHARD W. BURNETT.
